J. E. GREEN.

SILO.

APPLICATION FILED NOV. 11, 1915.

1,220,978.

Patented Mar. 27, 1917

UNITED STATES PATENT OFFICE.

JOSEPH E. GREEN, OF NORTH MANCHESTER, INDIANA.

SILO.

1,220,978.

Specification of Letters Patent. Patented Mar. 27, 1917.

Application filed November 11, 1915. Serial No. 60,864.

To all whom it may concern:

Be it known that I, JOSEPH E. GREEN, a citizen of the United States, residing at North Manchester, in the county of Wabash and State of Indiana, have invented certain new and useful Improvements in Silos; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in silos, generally, more particularly to door constructions or closures therefor.

The invention consists therefore of certain structural features, substantially as herein-20 after fully disclosed and defined by the appended claim.

Referring to the accompanying drawings:

Figure 1 is a vertical sectional view through the doors taken on line 5—5 of Fig. 2.

Fig. 2 is a fragmentary elevation illustrating the door construction, and

Fig. 3 is a fragmentary horizontal sec-25 tional view taken on line 7—7 of Fig. 1.

Like numerals of reference indicate the same parts throughout the several figures.

In carrying out my invention, I employ two channel iron frame-pieces 8 suitably positioned to constitute the door-way or entrance of the silo. At intervals the channel iron frame-pieces 8 are perforated to receive the eye-bolts 9 to which the ends 10 of the ties 6 are fastened as shown in Fig. 3.

The door opening of the silo is provided with the usual cross-members 13 connecting the two vertical channel iron members together, and I prefer to have every alternate cross-member 13 pivoted at one end as at 14 and provided at the other end with a slot 15 for engagement with the outstanding pin or bolt 16, so that every alternate cross-member 13 can be swung upwardly on its pivot 14 so as to enlarge the opening for the ready handling of the ensilage. The bars 13, which primarily serve as "rounds or treads" of a ladder, as commonly provided for in silos, for ready access to the fastenings of the doors or closures, as in operating the closures or doors for the removal of the ensilage, are utilized or employed as means with which the closure fastenings coöperate

for securing the closures or doors in fastened closed or fastened open position, as before indicated, the closures or doors, of course, being presented interiorly to the ensilage.

Referring to the doors 17 it will be seen that each is provided preferably with an ogee formation at its top and bottom edges which I prefer to cover with a felt or other suitable material 18, so that when the doors 60 are in closed position they will insure a tight closure, and I prefer to have the doors 65 slightly overlap the inner face of the channel iron members 8, the overlapping edges of the said doors being also provided with 70 a strip of felt or other suitable material 19.

Each of the doors 17 has pivoted thereto at 20 a yoke 21 which in turn is pivoted to opposite eye-bolts 9, so that each of said doors 17 can be swung from a closed position as indicated in dotted lines in Fig. 5 up into an open position as indicated in said figure. It will also be seen that all of the doors 17 are provided near their bottom edges with pivoted hook members 22, the 75 80 depending hook end 23 engaging one of the cross-pieces 13 to lock and hold the door in a closed position. It will also be seen that the said hook members 22 are brought into proper operative position when the door is 85 in a raised position for effective engagement with another of said cross-pieces 13 to lock the said door in a raised position. By means of this construction the same locking or fastening means is employed for locking the doors, both in a closed and an open 90 position, thus simplifying the construction and providing an arrangement which is extremely convenient and at the same time strong, durable and efficient.

Having thus fully described the invention it is apparent that the construction is susceptible of certain changes and alterations, and I consider myself clearly entitled to all such modifications as fall within the scope 95 of the appended claim.

I claim:

In a silo, the combination with channel-iron frame members forming the sides of the entrance-opening, of closures for said entrance-opening, said closures being superposed with respect to each other, hangers of general U-outline having their transverse portions pivotally connected to said closures, nearer the bottom edges of said closures 105 110 than their top edges, the terminals of the arms of said hangers having connection with

said entrance-opening sides to enable the hangers to be swung upon their connections with the closures and said entrance-opening sides to cause the closures to be moved from 5 their closed positions to their open positions, and a hooked fastening connected to each closure near its bottom edge, said entrance-opening side forming members having arranged thereacross transverse members 10 at points upon the edges of said side-forming members opposite the edges thereof to which the closures are applied, said transverse members forming ladder rungs, certain of said transverse members being arranged 15 with definite predetermined relation to said hooked fastening to provide for engagement therewith when said closure is in a normally lowered position, said certain ladder rungs being disposed with definite

predetermined relation to said hooked fastening when said closure is in a raised position to receive said hooked fastening to retain the said closure in such raised position, whereby the swinging of a closure, either into a lowered or into a raised position will 20 dispose its hooked fastening coincident with a predetermined positioned transverse member for engagement therewith, to the end that the said hooked fastening is a common element for retaining the closure both in a 25 raised and in a lowered position.

In testimony whereof I affix my signature in presence of two witnesses.

JOSEPH E. GREEN.

Witnesses:

CALVIN ULREY,
B. F. OBER.
